UNITED STATES PATENT OFFICE.

WILLIAM HOCHHAUSEN, OF NEW YORK, N. Y., ASSIGNOR TO THE EXCELSIOR ELECTRIC COMPANY, OF SAME PLACE.

SYSTEM OF ARC AND INCANDESCENT ELECTRIC LIGHTING.

SPECIFICATION forming part of Letters Patent No. 416,612, dated December 3, 1889.

Application filed January 11, 1884. Serial No. 117,106. (No model.)

To all whom it may concern:

Be it known that I, WILLIAM HOCHHAUSEN, a citizen of the United States, and a resident of New York, in the county of New York and State of New York, have invented certain new and useful Improvements in Systems of Arc and Incandescent Electric Lighting, of which the following is a specification.

My invention is designed primarily to make practicable the running of arc and incandescent electric lamps on the same general circuit, and is intended more especially for application to those systems of lighting in which incandescent lamps are arranged in multiple-arc branches upon a line on which arc lamps are run in series. In systems of this kind as hitherto operated there has been danger of rupture of the whole circuit and liability to the destruction of all the incandescent lamps from the sudden turning out of an arc lamp or lamps on the circuit or from the accidental breakage of one or more of the incandescent lamps in a set of multiple-arc branches. In the case of the turning out of an arc lamp the resistance is suddenly lowered, and if the current-governor of the dynamo-machine does not act with promptness more current passes through the incandescent lamps than they can bear, and one or more of them are broken. The breaking of any one or more incandescent lamps endangers the lamps in the remaining multiple-arc branches, the number of paths for the current having been thus diminished, so that each of the remaining lamps is obliged to carry more current. This action might result in the breakage of all the lamps. The same danger may arise from the breakage of any lamp in a multiple-arc branch through inherent weakness even when carrying a normal current. My invention overcomes entirely all danger arising from these causes and absolutely protects the lamps in the multiple-arc branches from injury by excess of current, and likewise makes a rupture of the general circuit from the above causes impossible.

My invention consists, principally, in combining with the incandescent lamps arranged

in multiple arc a spring or equivalently-actuated shunting-switch, said switch being normally (or while the lamps are working properly) held out of operation by a catch or detent and automatically released by any suitable means, as by an electro-magnet, upon an abnormal flow of current in a multiple-arc branch, which branch may be a branch containing a lamp, but is preferably a separate branch containing a high-resistance magnet.

My invention consists also in certain details and combinations that will be described in connection with the accompanying drawings, and will then be pointed out in the claims.

In the accompanying drawings, Figure 1 is a plan of an apparatus embodying my invention, showing the devices assembled in a box or casing. Fig. 2 is a side view of the box, showing the arrangement of the automatic switch. Fig. 3 is a section on the line $x-x$ of Fig. 1. Fig. 4 is a diagram of the connections of the devices. Fig. 5 illustrates a modified detail.

A indicates the box or casing containing the apparatus, and B' B² B³ binding-posts for the attachment of the conductors leading to the incandescent lamps arranged in multiple arc and of the line or general-circuit conductors that include the arc lamps or other apparatus arranged in series with one another and with the incandescent lamps.

C indicates a switch connected at its pivot in any ordinary or suitable way with the general-circuit wire 5 and at its free end adapted to be forced between and make contact either with springs D' D', that are connected with one pole of the circuit for the incandescent lamps, or with springs D² D³, that are directly connected with the binding-post B', to which the general-circuit wire 5 on the other side of the apparatus is connected. A button or handle d serves to operate the switch to throw it against springs D' D', while a spring D³ or a weight or equivalent actuating device tends to hold the switch in contact with D' D². In the latter position the incandescent lamps are shunted or cut out. The springs D' and D² are so arranged that the switch

shall make contact with one set before breaking contact with the other.

E indicates a detent-lever having a detent or catch at e, that engages with the switch-lever C and holds it in contact with the springs D' D' when it has been thrown to that position. The detent-lever is held in this position by an electro-magnet F acting on the lever as on an armature or by other suitable devices, and is drawn in the opposite direction by a spring e² or weight to release the switch on the operation of suitable devices (to be presently described) that come into play upon an abnormal flow of current in a multiple-arc branch or in an extra branch around the incandescent lamps.

At 6 6 are indicated the local or sub conductors leading to the multiple-arc branches a a a a, &c., each containing an incandescent electric lamp b b or other translating device. One of said conductors 6 is connected with binding-post B', and so directly with the general circuit containing the arc lamps. The other conductor 6 is connected to binding-post B³, from which connection is made by any suitable wires with the springs D' D'.

In the present instance the connection is shown as made through a wire 8 and strap 15, connecting with a local binding-post g, mounted on a block that supports a contact-stop h for an armature G, and from said binding-post through wires 9 and electro-magnet F to the contacts D' D'. When this circuit is closed by the throwing of the switch C to D' D', the magnet F is energized and sets the detent e so as to hold the switch C in position to keep the incandescent lamps b b and other apparatus (to be now described) in circuit.

H indicates an electro-magnet of high resistance, which when the contacts at D' D' are closed is in a multiple-arc branch or in a branch around the incandescent lamps, connection of the magnet-terminals for this purpose being made, as indicated in the figures, to post g and wire 9 on one side and to local binding-post h² on the other side, the latter being connected to the post B', with which the incandescent-lamp circuit is connected.

I indicates an armature-lever for said magnet, controlling two normally-open supplemental branches, one containing an artificial resistance K, normally equal to the resistance of a lamp b when the latter is hot, and the other containing an incandescent lamp L, mounted in a suitable holder on the box or otherwise. Armature-lever I is connected with binding-post h², and so with main line at B', and serves, when drawn forward against the action of its retractor by a predetermined increase of current in H, to close, by means of spring k, an insulated contact l, connected, through wire 10 and resistance K, with binding-post g and contacts D' D'. A second contact M for the lever I is connected, through wires 12 and lamp L, with g and D' D', and is set just out of range of the lever when contact is first made at l, so that a further in-

crease of current in magnet H beyond that necessary to close the circuit to K is required in order to close the circuit to lamp L.

The resistance K is mounted in any suitable manner, and consists of a spiral or spirals of wire fixed at its ends and having its successive turns in such close proximity that the expansion of the wire by the heating effects of a current flowing through it may cause the successive turns to come into more or less close connection, and thus lessen the resistance by short-circuiting the turns. By this construction, when the resistance branch is closed, a further increase of current through the branches will, by heating the resistance, automatically diminish its amount, so that its shunting capacity will automatically increase and the safety of any apparatus in the branch or branches to which it forms a shunt will be still further assured.

The supplemental armature G is magnetically connected at one end to the core of H and its other or free end is presented to the opposite end of the core of magnet H. The frame and core of magnet H, and therefore the armature G, are connected with the conductor 9, leading from contacts D' D' to the frame and then to the magnet F, while the contact-stop h for said armature is connected with the post g, so that, as will be obvious, when the armature G is drawn against its contact the magnet F will be short-circuited, and the retractor e² will thereupon disengage the switch and detent, so that the switch may be thrown by its spring or other device. A button on the lever E permits a release of the switch to be also effected by hand at will. The retractor for armature G is so adjusted that the shunt to F can only be closed upon an abnormal flow of current in H beyond that necessary to close contact M and of such amount that a breakage of all the incandescent-lamp branches a a is threatened.

In order to prevent spark at the contacts D² D² when the switch is operated to break the shunt around the lamps and to throw the lamps into circuit, I provide resistances R R R, of German silver wire or other suitable material, arranged in multiple arc and connected, respectively, with the three contact-springs r r r on one side, as indicated, and on the other with the main line through D² D² and B'. The switch C leaves the springs r r r in succession after breaking connection with D² D², thus gradually increasing the resistance in the shunt and at the same time forcing current to the lamps through D' D'. When the switch is in contact with the three springs r r r, the resistance is obviously one-third that of one coil R; but when it leaves the last spring r the resistance is equal to that of a whole coil.

The general operation is as follows: The switch C being in the position shown in the drawings, the short or cut-out circuit through D² D² around the lamps is broken and the lamps b b are in multiple arc on the same

general circuit with the arc lights indicated at N. The magnet F, which is of low resistance and has been placed in the general circuit by the turning of the switch to contacts 5 D'D', is energized and holds lever E against its retractor in such position that the catch e engages with C and holds the latter. Current passes also through the high-resistance magnet H; but the armature-lever I therefor 10 remains held against its back-stop by the action of the retractor for I, which is suitably adjusted to hold it in this position so long as the flow of current in H remains normal. The supplemental branches containing, respectively, the resistance K and the lamp L therefore remain open. If from any cause 15 the current in H increase to a predetermined amount, so as to overcome the retractor for I, either by reason of the extinction of an 20 arc lamp and consequent increase of current on the general circuit or by reason of the breakage of a lamp b and consequent rupture of a multiple-arc branch, thus throwing more current onto the remaining branches, 25 said magnet H will draw up its armature and close the circuit through resistance K, thus providing an additional path for the current and withdrawing a proportionate amount of current from the lamp branches a, so as to 30 restore the flow of current on the latter to normal or proper amount. If from any reason—as, for instance, the breakage of an additional lamp b—the current in H increase still more, the armature-lever I will close the 35 circuit of lamp L through M, and said lamp will begin to glow, indicating a dangerous state of the lamps b b, &c., remaining in circuit. If the current in the various branches now in circuit increases still further, the 40 resistance-wire coils of K may begin to automatically shunt themselves, and by thus, in a measure, withdrawing current from the lamps b protect them to a certain extent. During these actions the armature G is stationary, its retractor being so adjusted that 45 the magnet H can only attract it to close circuit at h when there is an excessive flow of current in H, due to the breakage of a number of branches a a or to other abnormal 50 conditions tending to affect the safety of such lamps and the integrity of the general circuit by obliging such lamps to carry a greater current than they can bear. When these 55 conditions come into existence, the armature G is drawn down, closing the contacts at h and shunting magnet F, which thereupon releases its hold on its armature, thus permitting the switch C to be automatically thrown over by spring D³, so as to break the circuit 60 to the lamps and complete the circuit for the general conductor 55 around them, as already explained.

I do not limit myself to any particular mechanical construction of detent or catch devices, nor to the form or construction of the magnet for producing the desired closures of circuit or operation of the detent.

I have herein shown the armature G as actuated by the magnet that controls the resistance R and lamp L; but it might obviously be actuated by a separate magnet, as indicated in Fig. 5, placed, if desired, in a separate branch.

In a prior application filed by me August 6, 1883, No. 102,986, I have claimed the combination, with a group of incandescent lamps arranged in multiple arc upon an arc circuit, of an extra branch around the group of lamps, an electro-magnet connected to the circuit, and an electric switch controlled thereby for diverting current through said branch to protect the lamps from injury on a dangerous increase of current in the multiple-arc branch. No claim is therefore made in the present application to this combination.

What I claim as my invention is—

1. The combination, with a group of incandescent lamps arranged in multiple arc, of a shunting-switch, detaining mechanism for normally holding said switch open, and means 90 for releasing said detaining mechanism upon an abnormal flow of current in a multiple-arc branch.

2. The combination, with incandescent lamps arranged in multiple arc, of a switch 95 for completing, when in one position, the circuit to the multiple-arc branches and when in the other position closing a shunt around them, means normally tending to actuate the switch so as to close the shunt, and a detent 100 for holding the switch, said detent being controlled directly or indirectly by a magnet in a multiple-arc branch.

3. The combination, with lamps arranged in multiple arc, of a shunting-switch, a de- 105 tent-magnet therefor in the connection to the lamps, and a circuit-controlling magnet in a multiple-arc branch, as and for the purpose described.

4. The combination, with incandescent 110 lamps arranged in multiple arc, of a supplemental branch containing a resistance, a magnet in a multiple-arc branch controlling the supplemental branch, a shunting-switch for shunting the lamps, and means for releasing 115 said switch upon an extinction of a number of lamps or an abnormal flow of current in a multiple-arc branch.

5. The combination, with incandescent 120 lamps arranged in multiple arc, of a shunting-switch, a detent-magnet therefor in the circuit to the lamps closed by said switch, and means for short-circuiting said magnet upon a predetermined increase in the flow of current in a multiple-arc branch.

6. The combination, with incandescent 130 lamps arranged in multiple arc upon an arc-light circuit, of a shunting-switch, a detent therefor, and means for operating said detent upon a predetermined increase in the flow of current in a multiple-arc branch, so as to release the switch.

7. The combination, with incandescent lamps arranged in multiple arc, of two nor-

5 mally-open supplemental branches, one containing an artificial resistance and the other an incandescent lamp, and means for closing said branches in succession upon predetermined increases in the flow of current in the multiple-arc branches.

8. The combination, with the multiple-arc branches, of a normally-open supplemental branch containing a resistance-coil having 10 its turns in close proximity and capable of free movement, so that the heating of the coil may cause the successive turns to come into contact and thus lessen the resistance, as and for the purpose described.

15 9. The combination, with a lamp or other translating device *b*, of the branch around the same, the artificial resistance-coil constructed in the manner described, so as to automatically decrease in resistance, and 20 means for closing said branch, for the purpose described.

10. The combination, with a group of incandescent lamps arranged in multiple arc, 25 of a normally-open branch of low resistance around them and means for automatically closing said branch upon an abnormal increase of current in a multiple-arc branch.

11. The combination, with a group of incandescent lamps arranged in multiple arc,

of a normally-open branch around them and 30 means for automatically closing said branch and simultaneously breaking the circuit to the group of lamps upon a dangerous increase of current in a multiple-arc branch.

12. The combination, with a group of incandescent lamps arranged in multiple arc, 35 of a normally-open branch containing an incandescent lamp and means for closing said branch upon a predetermined increase in the current of a multiple-arc branch.

13. The combination, with a group of incandescent lamps arranged in multiple arc, 40 of a supplemental branch containing a resistance, a magnet in a multiple-arc branch controlling the same, a normally-open short circuit, and a controlling electro-magnet therefor adjusted to cause said shunt to be closed upon an abnormal increase in the flow of current in a multiple-arc branch, due to the extinguishment of an abnormal number of the 45 lamps in the multiple-arc branches.

Signed at New York, in the county of New York and State of New York, this 10th day of January, A. D. 1884.

WILLIAM HOCHHAUSEN.
